UNITED STATES PATENT OFFICE.

EZRA W. WITTER, OF MEDINA, OHIO.

DENTAL APPLIANCE.

SPECIFICATION forming part of Letters Patent No. 730,184, dated June 2, 1903.

Application filed April 19, 1902. Serial No. 103,784. (No model.)

To all whom it may concern:

Be it known that I, EZRA W. WITTER, a citizen of the United States, residing at Medina, in the county of Medina and State of Ohio, 5 have invented a new and useful Dental Appliance, of which the following is a specification.

My present invention relates to a novel dental appliance designed more particularly to 10 facilitate operations upon the teeth of the lower jaw.

The object of the invention is to provide a 15 simple and inexpensive device which when applied will clamp one or more teeth and be securely retained thereby in position to depress the tongue and retract the cheek in order to keep the tooth being operated upon perfectly dry and to protect the cheek and tongue from being brought into contact with 20 the instrument.

A further object of the invention is to utilize the device intended primarily for the purpose stated for the further purpose of reflecting the light upon the tooth being ground, 25 filled, or otherwise treated and for the purpose of holding cotton or other absorbent material against the gums to absorb the moisture.

To the accomplishment of these objects and 30 others subordinate thereto the invention in its preferred embodiment comprehends a substantially U-shaped frame comprising a pair of relatively adjustable side sections or plates having hinged connection at one end and provided with a regulating or adjusting device 35 for causing the plates to approach and clamp against the opposite sides of the teeth or to recede for the purpose of permitting the removal of the device from the mouth. One or 40 both of the plates is provided with an adjustable tooth-engaging member or clamp by means of which any particular tooth may be engaged, and the frame is equipped with a detachable handle to facilitate the insertion 45 of the device into the mouth and capable of removal after the frame has been properly positioned.

Further objects of the invention and other novel features will appear during the course 50 of the succeeding description of that embodiment of the invention, which for the purposes

of this application is illustrated in the accompanying drawings.

In said drawings, Figure 1 is a general view showing the device applied as in use. Fig. 2 55 is a bottom plan view of the appliance with the handle broken away and showing an adjusted position of the member 3 in dotted lines. Fig. 3 is a transverse sectional view. Fig. 4 is a detail sectional view showing the 60 means for regulating the frame. Fig. 5 is a detail perspective view of the member 3, and Fig. 6 is a sectional view of a modification.

Like numerals of reference are employed to designate corresponding parts throughout 65 the several views.

The device or instrument proper is in the form of an approximately U-shaped frame 1, composed of side plates or sections 2 and 3, of thin highly-polished metal, their contiguous longitudinal edges being properly shaped to conform generally to the contour of the jaw on one side—that is to say, the open-ended slot 4 defined between the plates 2 and 3 has a slight longitudinal curvature corresponding to the arrangement of a series of teeth, against the opposite sides of which the inner edges of the plates 2 and 3 are clamped. 75

The inner or left-hand plate 2 is designed to constitute a tongue-depressor and is therefore transversely curved, as indicated in Fig. 3, to promote as far as possible the comfort of the patient, and at its front end said plate is provided with a laterally-disposed bridge portion 5, pivoted at the rear corner of its extremity to the plate 3, as by a pintle 6. The plates are thus afforded a hinged connection, which permits the contraction or expansion of the frame to facilitate the engagement or disengagement of the teeth and to regulate 90 the width of the slot or opening 4 for the purpose of accommodating the device to the mouths of different patients.

The regulation of the frame or the relative adjustment of the plates is effected by means 95 of a small thumb-wheel 7, having a knurled periphery and located within a recess 8 in the front edge of the bridge portion 5 of the plate 2. This regulating-wheel has threaded connection with a screw-rod 9, received within a 100 cylindrical pocket 10 in the plate 2, the right-hand end of said rod being extended into a

socket 11, formed in the rear end of the plate 3 and terminally pivoted therein by a pintle 12, as shown.

The precise manner of effecting the connection of these parts is not essential, perhaps; but for the sake of a neat finish the rear side of the socket 11 is cut away to permit said socket to fit over the front edge of the bridge portion 5, and thus effect an interfitting relation of the plates at this point.

It will now be seen that since the regulating-wheel 7 is held against lateral movement its rotation will effect the endwise movement of the screw-rod 9, and as the pivotal connection of said rod with the plate 3 is eccentric to the hinge 6 the plates will be swung toward or away from each other, as may be desired.

I have stated that it is desirable to utilize the device for the purpose of concentrating the light directly upon the tooth or teeth being operated upon, and for this reason, as well as to conduce to the comfort of the patient, the plates are transversely inclined to cause them to assume an angular relation—that is to say, the inner or contiguous edges of the plates are depressed, giving the frame a trough-like shape. This peculiar configuration enables the inner edges of the plates to engage the teeth directly above the edges of the gum and presents the raised bridge portion 5 directly over one or more teeth in advance of those engaged by the plates.

If desired, the device may also be utilized to hold cotton or other absorbent material in place, as it is obvious that such material could be held against the gums and within the salivaduct of the cheek by the plate 3, which serves, primarily, as a cheek-retractor.

The device as thus far described comprehends a complete embodiment of my invention in one aspect thereof and is possessed of great utility without further addition. I prefer, however, to provide for the more secure retention of the frame by mounting an adjustable tooth-clamp 13 upon the inner longitudinal edge of the plate 3. This clamp is in the form of a spring-clip the leaves or plates 14 and 15 of which engage the opposite faces of the plate 3 to retain the clamp. The clamp proper is disposed at an angle to the plate 3 to assume a horizontal position and is provided with a recess or seat 16, which conforms approximately to the contour of the tooth to be engaged. This clamp may be moved along the cheek-retracting plate 3 to any desired point, where it is frictionally retained in position to engage a tooth, and thus insures the rigid retention of the device as a whole. I also contemplate the employment of a detachable handle 17, disposed at an angle to the frame and having a threaded socket 18 for the reception of a threaded shank 19, extending tangentially from the rear end of one of the members or plates, as shown.

In Fig. 6 I have shown a modified construc-

tion which may be desirable in some instances—as, for instance, where the teeth are of such form that the attachment of the device is comparatively difficult. In this case 70 a second tooth-clamp 20 would be mounted on the inner edge of the tongue-depressing plate 2, and the clamps 20 and 13 would be connected by a bridge-wire 21, designed to pass over the teeth and perhaps lie partially 75 between the same.

When it is desired to grind down a tooth of the lower jaw for the purpose of shaping the same for a gold cap or when the attachment of the device is desired to facilitate the 80 filling or other treatment of a tooth, the plates are spread apart by the manipulation of the regulating-wheel 7, and the frame carried by the handle 17 is inserted in the mouth and positioned to bring the tooth or teeth to be 85 operated upon within the slot 4. The wheel 7 is now rotated to clamp the plates firmly against the opposite sides of the teeth, the tooth-clamp 13 or the clamps 13 and 20, as the case may be, having first been properly 90 adjusted to engage an individual tooth. The handle 17 is now unscrewed from the shank 19, and as the tongue will be depressed, the cheek retracted, and the light concentrated upon the teeth the operation may be proceeded with without danger of having the instrument accidentally brought into contact with the gums, tongue, or cheek and without danger of moisture reaching the tooth, even should the patient shut his mouth. 100

It may be noted that the device is particularly useful in connection with grinding teeth for gold caps, because the hand-mirror ordinarily employed and often mutilated by the stone may be dispensed with in consequence 105 of the reflective quality of the polished plates.

It is thought that from the foregoing the construction, mode of manipulation, and many advantages of my invention will be clearly apparent; but while the present embodiment thereof is thought at this time to be preferable I desire to reserve to myself the right to effect such changes, modifications, and variations of the illustrated structure as may be properly comprehended within the 115 scope of the protection prayed.

What I claim is—

1. A dental appliance comprising a pair of tongue - depressing and cheek - retracting plates arranged to clamp the teeth between 120 their opposed edges, and means for positively adjusting said plates.

2. A dental appliance comprising a pair of tongue - depressing and cheek - retracting plates disposed to clamp the teeth between 125 their opposed edges, said plates being reflective and oppositely inclined transversely.

3. A dental appliance comprising a pair of tongue - depressing and cheek - retracting plates having hinged connection and designed 130 to clamp the teeth between their opposed edges, said plates being reflective and oppo-

- sitely inclined transversely, and means for retaining said plates in their adjusted positions.
4. A dental appliance comprising a pair of tongue-depressing and cheek-retracting reflective plates, oppositely inclined transversely and having hinged connection at one end to provide for their relative adjustment to fit different teeth, and means for positively adjusting the plates.
5. A dental appliance comprising a substantially **U** - shaped frame composed of hingedly-connected tongue-depressing and cheek-retracting side plates and an intermediate bridge portion, and a regulating device mounted in said bridge portion to adjust the plates.
15. A dental appliance comprising a substantially **U**-shaped frame composed of relatively adjustable tongue-depressing and cheek-retracting plates, and a detachable handle extending from the closed end of said frame.
20. A dental appliance comprising tongue-depressing and cheek-retracting plates, and a tooth-clamp having the form of a spring-clip frictionally engaging the edge of one of the plates and adjustable to different positions thereon.
25. A dental appliance comprising a pair of hinged tongue-depressing and cheek-retracting plates arranged to be clamped upon the teeth, a regulating-wheel, and a screw-rod operated by the wheel to effect the relative adjustment of the plates.
30. A dental appliance comprising a pair of hinged tongue-depressing and cheek-retracting plates, a screw-rod pivoted to one plate at a point eccentric to the hinge, and a regulating-wheel retained by the other plate and having threaded connection with said rod.
35. A dental appliance comprising a substantially **U** - shaped frame, composed of hinged side plates oppositely inclined transversely and an intermediate elevated bridge portion.
40. A dental appliance comprising tongue-depressing and cheek-retracting plates, and a tooth-clamp carried by one of said plates.
45. A dental appliance comprising tongue-depressing and cheek-retracting plates, and a tooth-clamp adjustable upon one of said plates.
50. A dental appliance comprising tongue-depressing and cheek-retracting plates, and a tooth-clamp adjustable along one of said plates.
55. A dental appliance comprising tongue-depressing and cheek-retracting plates having relative adjustment, and a tooth-clamp adjustable along one of said plates.
60. A dental appliance comprising reflective tongue-depressing and cheek-retracting plates having hinged connection and oppositely inclined transversely, a regulating device for adjusting the plates relatively, and a tooth-clamp adjustable along one of said plates.
65. A dental appliance comprising a pair of hinged plates arranged to engage the teeth, a shank extending from one of said plates, and a handle detachably fitted to said shank.
70. A dental appliance comprising tongue-depressing and cheek-retracting reflective plates having hinged connection and oppositely inclined transversely, an elevated bridge portion connecting the plates at one end, a screw-rod pivoted to one plate and extended into the other, a regulating-wheel for adjusting the rod, a shank extending from one plate, and a handle detachably fitted to the shank.
75. In testimony that I claim the foregoing as my own I have hereto affixed my signature in the presence of two witnesses.
